ALTERNATING CURRENT SWITCHING DEVICE

Fritz Kesselring, Zollikon, Zurich, Switzerland, assignor to FKG Fritz Kesselring Geratebau A. G., Bachtobel-Weinfelden, Thurgau, Switzerland, a corporation of Switzerland

Application March 18, 1953, Serial No. 343,077

19 Claims. (Cl. 317—11)

This invention relates to a magnetic switching device and is more particularly directed to a novel switching apparatus having a voltage path in parallel with the switching unit.

In the prior art arrangements for magnetic rectifiers and other similar devices which have multiple contact make and break operations in relatively short periods of time, the problem of sparking and pitting at the cooperating contacts during disengagement always arises.

Heretofore so called commutating or saturable reactors were connected in series with the cooperating contacts in order to reduce the interrupting capacity of a switching means. In this arrangement, the rapid rate of decrease of the load current caused the saturable reactor to unsaturate and thereby present a high impedance in series with the switch device and load. That is, a step was created during which period of time the contacts could be safely disengaged with little or no sparking or pitting.

However, this prior art arrangement has two main disadvantages. In the first place, it is essential to have a relatively long step period to insure sufficient time to initiate contact disengagement and insure that there is complete separation of the cooperating members in order to prevent backfire or backflow of current. In order to make the device safety-proof, therefore, it was essential to extend the step period which resulted in reducing the efficiency of the rectifying unit. In my novel apparatus, I achieve a substantially spark-free interruption without the necessity of a large commutating reactor and thereby increase the efficiency of the device. The second main disadvantage of the commutating or saturable reactor is its complexity and expense. The commutating or saturable reactors have circular iron cores composed of thin walled nickel iron. These devices are very expensive due to the high cost of the raw material, the thin gauge of the sheet metal which must be a few hundredths of a millimeter in thickness, the manufacturing difficulties encountered in winding the main current coil and the required auxiliary equipment such as the direct and alternating current biasing windings.

In the novel device of my invention, the above noted disadvantages encountered when using a commutating reactor are substantially eliminated.

In my novel apparatus, the current to be interrupted is intermittently sub-divided into component currents by means of parallel connections. That is, a current path and a parallel voltage path is provided for the flow of load current. The current path which is the branch wherein current interruption will take place is provided with a series rectifier which is designed for only a fraction of the source and load voltage but is capable of withstanding the total load current.

In parallel with this switching rectifier current path is a voltage path which is provided with rectifying means. This series rectifier in the voltage path differs from the series rectifier in the current path in that it is designed to

2

be capable of withstanding negative breakdown voltage equal to the maximum voltage of the source although it is only capable of withstanding a fractional portion of the load current.

5 In addition to the rectifying unit in the voltage path, a series inductor is provided. Although the current will divide between the current and voltage paths are predetermined times within the operating cycle, the circuits are designed so that the current flow in the current path will lead to total current. This arrangement insures that the current flowing through the current path will pass through current zero prior to the time that the total current passes through the current zero. Thus, the device is so arranged that circuit interruption in the current path will commence immediately following the current zero therein to thereby insure substantial currentless interruption. That is, whereas in the prior art it was essential to provide a commutating reactor in series with the interrupting means to achieve a step current during the switching operation, the instant invention provides a parallel path in such a manner that the current flow in a current path is zero at the time of circuit interruption without the necessity of a commutating reactor.

20 Thus, it will be noted that the current path can successfully interrupt the circuit under current zero conditions and during the opening operation, the rectifier in the voltage path will prevent backflow of current. In this novel arrangement the current flow in the current path is relatively large during the major portion of the operating cycle.

25 Since the novel apparatus merely requires that a lagging current flow in the voltage path only immediately preceding and during the current interruption, additional means can be provided to achieve this effect. That is, 30 rather than have current flow through the voltage path during the major portion of the effective cycle of operation and introduce additional losses, means may be provided to insure that current flows through this current path only when it is essential to have current zero interrupting the operation.

35 Thus, my invention also sets forth a novel arrangement wherein the IR losses in the voltage path will be maintained at a minimum by providing means which will divert the current to this voltage path just prior to the zero passage of the total current. This is achieved by 40 providing a rectifier unit in the voltage circuit which may be triggered off from the line circuit. That is, a controllable rectifier replaces the above mentioned rectifier in the voltage path. Thus, for example by providing a diode having a predetermined breakdown voltage, it is 45 possible to supply the plate voltage thereof from predetermined current conditions in the load to thereby insure that this unit will breakdown from one to five milliseconds before the zero passage of the main current.

50 As heretofore noted, one of the major problems of repetitive circuit interruption for magnetic rectifiers and other switching devices is the burning and pitting of the contact material during current interruption. However, 55 it is not only essential to have substantially currentless interruption but it is also necessary to provide means to prevent the backflow of current through the switching means before it has fully interrupted the circuit.

55 As above noted, a small rectifying unit may be inserted in series with the interrupter contacts and rectifier operations. For load currents of a thousand amperes the return current will only be one or two tenths of an ampere and hence, the blocking or negative breakdown voltage of the components will not have to be very large. However, when the unit is operated for larger loads such as 70 five to ten thousand amperes, the return current will be much larger.

For installations which will be used with relatively large loads, a small saturable reactor may be inserted in series with the interrupting unit and rectifier of the current path to thereby create a short step during current interruption. It will be noted that since the voltage parallel path provides a substantially currentless interruption that the additional above mentioned saturable reactor will not have to be a large complex unit and hence, the losses introduced thereby and the expense thereof will be relatively small as compared with the prior art commutating reactor type of magnetic rectifier.

It will also be noted that my device may be provided with an arrangement wherein a small commutating reactor can be provided for the voltage path.

In the operation of magnetic rectifiers wherein many current interruptions must occur within a very short period of time and which requires that the voltage path be phase shifted from the current path results in an arrangement wherein a large current magnitude may be required in a current path in order to obtain sufficient phase shift and hence, would require not only a large and expensive series rectifier therein but would also introduce large IR losses. Also due to the frequent period current variations in both the current and voltage path, large back E. M. F.'s will be caused by the inductances in each circuit thereby creating additional losses in the circuit.

In order to overcome the above mentioned disadvantages, a commutating reactor may be provided in the parallel voltage circuit to considerably reduce the speed of current variation in the vicinity of current zero passage thereby eliminating the above mentioned decrease.

That is, a commutating reactor can be properly biased to be effective during the switching operation.

It will also be noted that losses may be introduced into the circuit due to the series rectifier of the current path since this rectifier must carry the full load current. However, these losses can be considerably reduced by providing a parallel saturable reactor for the series current path rectifier which is capable of diverting the current therefrom. Thus, during the major portion of the operating cycle, a substantial portion of the load current will flow through the winding of the saturable reactor and thereby be diverted from its parallel connected rectifier. That is, as is well known in the art, after a predetermined magnitude of load current has been reached, the saturable reactor will be saturated and present substantially no reactance to the circuit. Thus, during this condition, the commutating reactor will be similar to a low inductance unit in parallel with the series rectifier to thereby relieve the rectifier from carrying a load current and hence, reduce the losses which would otherwise result. However, when the load current approaches zero the decrease in current magnitude and the rapid rate of change of the current will cause the reactor to unsaturate.

As is well known in the art, this will have the effect of presenting a substantially large reactance or inductance to the circuit during the period when it is unsaturated. Hence, during this portion of the cycle, when the current is bridged and going through current zero, the reactor will be equivalent to a high reactance in parallel with the series rectifier and hence will not divert any current therefrom and hence, all of the load current will again flow through the series current path rectifier.

It will be noted that my novel invention although readily adaptable to the achievement of rectification of alternating current is not limited thereto.

In one modification utilizing the basic parallel path principle of my invention, it is possible to provide a fast acting alternating current switch. In this arrangement, the series rectifier in the current path is shunted during normal operation by a switching device. It is only during desired current interruption that the switching device is opened to thereby insert the series rectifier unit in series with the load. In this arrangement, the current interrupting means, although capable of interrupting maximum

load current need only have minimum interrupting requirements due to the parallel voltage path. However, the series rectifying unit in the parallel voltage path is capable of withstanding the entire source reverse voltage.

- 5 Additional means may be provided in the voltage path such as a series switch which may be opened after the main line has been interrupted. This series voltage switch will open on a currentless line and relieve the voltage path rectifiers from blocking the source voltage.
- 10 Accordingly, a primary object of my invention is to provide a novel switching unit wherein current interruption can be achieved without the necessity of a large commutating or saturable reactor.

Another object of my invention is to provide an alternating current magnetic switching means having a current and a voltage path wherein the design of the circuitry results in zero current flow through the current path during circuit interruption.

15 Another object of my invention is to provide a parallel path arrangement wherein the current in one path will lead the current in the second path so that interrupting means in the first path may be operated under substantially currentless operation.

20 Another object of my invention is to provide a novel rectifying unit which has relatively high efficiency.

25 A still further object of my invention is to provide switching circuitry which eliminates the relatively complex and expensive commutating reactors which were heretofore utilized in the prior art.

30 Another object of my invention is to provide novel circuitry wherein a rectifying unit having characteristics which enable it to carry large magnitudes of current although having a low negative breakdown voltage is operative only during the operating portion of the cycle and is effectively removed from the circuitry during the interrupted portion of the operation.

35 Another object of my invention is to provide novel circuitry for a switching device wherein a rectifying unit having a high negative breakdown voltage and little capacity to carry large currents is effectively introduced in the circuit during the interrupted portion of the operation and effectively removed from the circuit during the major portion of the operating cycle.

40 Still another object of my invention is to provide switching means wherein maximum utilization of the desirable operating characteristics of the components is achieved.

45 A still further object of my invention is to provide a parallel path arrangement for rectifier units in which the IR drops of the parallel voltage and current paths are relatively small.

50 A still further object of my invention is to provide a novel circuit in which the losses of the various components thereof is maintained at an absolute minimum.

55 Still another object of my invention is to provide a voltage path in parallel with the switching current path which is triggered or rendered effective immediately prior to and during the switching operation to insure maximum efficiency.

60 These and other objects of my invention will be apparent from the description when taken in connection with the drawings in which:

Figure 1 represents a circuit arrangement wherein my novel circuitry can be used for a magnetic rectifier. This arrangement provides a current path which contains the switching apparatus and a current rectifier and has a parallel voltage path containing a voltage rectifier and inductance.

Figure 2 is a voltage-current versus time curve illustrating the electrical conditions within the circuitry of Figure 1 existing during a complete cycle of operation.

Figure 3 is a circuit diagram of my novel circuitry used in a rectifier circuit. This figure represents an improvement over Figure 1 whereby RI losses can be substantially reduced.

Figure 4 is a voltage-current versus time curve of the various electrical conditions existing in the circuitry of Figure 3.

Figure 5 is a current versus time curve illustrating the magnitude and time division of the current between the series current rectifier and the current path and its parallel saturable reactor.

Figure 6 is a circuit illustration of the current and voltage path and illustrates circuitry which can be used to reduce and eliminate return current flow through the switching apparatus.

Figure 7 is an illustration of an improvement which can be used with the circuitry of Figure 1 or 3 to reduce or eliminate the undesirable back E. M. F. effect in the series inductor of the voltage path.

Figure 8 is a current-voltage versus time illustration of the electrical conditions existing in the circuitry of Figure 7.

Figure 9 represents a second electrical improvement which may be used to replace the arrangement of Figure 7 to reduce the losses and undesirable effects in the series inductor of the voltage path.

Figure 10 is a current versus time curve illustrating the electrical conditions existing in the circuitry of Figure 9.

Figure 11 is a circuit illustration of the manner in which my novel principle of parallel voltage in current paths may be applied to an alternating current switch.

Figures 1 and 2 illustrate my novel invention when used as a magnetic rectifier to convert the A. C. from the supply transformer 60a to D. C. for the load 10. The supply transformer 60a has a primary winding 61 and secondary windings 62 and 14. The secondary winding 14 of the transformer 60a is constructed so that the voltage V_0 obtained from the winding 14 and a portion of the secondary winding 62 will lead the voltage V which is obtained solely from the secondary winding 62. The control of the current flow from the secondary 62 to the load 10 is achieved by means of the switching device 20.

It will be noted that the switching device 20 is merely a schematic illustration of a switching unit similar to the one shown in Patent No. 2,732,451, dated January 24, 1956, and which is assigned to the same assignee as the instant application. This unit has a bridging contact 30 which is biased to the open position by the spring 40.

The armature 31 is provided with a closing winding 60 which is energized from the auxiliary winding 14 and a portion of the secondary winding 62 as will hereinafter be more fully described.

The switching device 20 is also provided with a holding coil 50 which is in series with the load. A rectifier 70 is provided in series with the bridging contact 30 to complete the current path of the rectifier.

As will hereinafter be apparent, the rectifier 70 is capable of withstanding the full load current although it is not required to have a high negative breakdown voltage. Connected in parallel with the current circuit comprised of the bridging contact 30 and the current rectifier 70 is a voltage path connected at the terminals A and B. This voltage path is comprised of a small inductance 90 and voltage rectifiers 80.

As will hereinafter be apparent, the voltage rectifiers 80 need not have the capacity to carry large load currents but instead have the characteristic of having a high negative breakdown voltage.

The closing winding 60 is energized through the circuitry comprising the left hand end of the secondary winding 62, the secondary winding 14, rectifier 12 and the adjustable rheostat 13.

The operation of the closing coil 60 is as follows:

As best seen in Figure 2, the voltage V across the secondary winding 62 lags the voltage V_0 which is obtained from the terminals of the supplementary winding 14 and the left terminal of the secondary winding 62. Thus, at time t_0 the voltage V_0 will be passing through negative and increasing in the positive direction.

The rectifier 12 will limit the current flow in the closing winding 60 from the combined windings 14 and 62 to a direct current. The rheostat 13 can be adjusted so that the magnitude of current flowing through the closing winding 60 can be controlled. Thus, the rheostat 13 can be adjusted so that the required ampere turns to move the armature 31 and the bridging contact 30 to the closed position against the opening force of the biasing spring 40 will occur at time t_1 . That is, in order to obtain maximum efficiency, it is desirable to have contact engagement occur at the time that the source voltage V emanating from the secondary winding 62 passes through zero in the positive direction. Thus, the leading voltage V_0 in combination with the adjustable rheostat 13 will enable the contact 30 to close as soon as the zero passage of the source voltage V occurs.

At a time t_1 , load current I will commence to flow in the circuit. It will be noted that due to the inductance in the circuit from holding winding 50 and the voltage winding 90 that the current I will not have an immediate high rate of rise. That is, instead of being a sinusoidal current, its immediate rate of rise will be small. This is a very desirable effect since possible bouncing or chattering of the bridging contact 30 would create considerable sparking if the current magnitude was too high. Thus, by insuring that the current builds up slowly, undue bouncing or chattering of the contacts during the closing operation will not cause sparking or pitting thereof due to the low magnitude of the current.

It will be noted that while the current I is on the positive increase, practically no current will be permitted to flow in the voltage path due to the inductive effect of the inductance 90. Thus, as illustrated in Figure 2, the current flow through the voltage path during a substantial portion of the positive build up of the main current I is substantially zero. Hence, the current I_1 , flowing in the current path will be substantially equal to the current I flowing in the load. When the rate of increase of the load current source starts to decrease, the inductor 90 will tend to maintain the current flow and thereby divert current into the voltage path. The current which is diverted into the voltage path from the point A is labelled I_2 , as seen in Figure 2.

As the load current I passes through its maximum value and the rate of decrease increases, the inductor 90 will tend to maintain the current at its present value and hence, an increasing amount of the load current I will be diverted into the voltage path.

Thus, as seen in Figure 1, from the time t_1' when a current starts to flow in substantial amounts in the voltage path, during the time t_2 the current diverted at point A through this voltage path will be continuously increased.

As best illustrated in the curve of Figure 2, it will be noted that during time t_1 to t_2 , the bridging contact 30 is closed even though the voltage V_0 is passing through the zero point during a portion of this period. That is, even though the closing coil 60 is not energized during the portion of the conducting cycle, the contacts 30 may be maintained closed by the holding coil 50 which is energized by the current I_1 .

Since the current I_1 represents a major portion of the large load current, the ampere turns of this holding coil 50 will hold the bridging contact 30 with high pressure contact.

As best illustrated in the current curve of Figure 2, the current I_1 flowing through the current path will lead the current I_2 flowing through the voltage path. As already noted the currents I_1 and I_2 are component parts of the load current I . Hence, since the load current I goes through the zero current point at time t_3 and since the current I_2 in the voltage branch lags the current I_1 in the current path, the current I_1 will have to pass through current zero at some time prior to t_3 . As illus-

trated in the figures, the current I_1 will pass through zero at time t_2 .

It will be noted that at this time t_2 , the current I_2 will be equal to the load current. Thus, during the period between time t_2 and t_3 , namely Δt , the current I_1 in the current path will be zero.

Since the rectifier 12 prevents energization of the closing coil 60 during the negative half cycle of V_0 closing coil 60 will not be energized during the period Δt . Also, since the current I_1 is at zero value during the time Δt , the holding coil 50 will not be energized. Hence, the biasing spring 40 will be able to dominate the bridging contact 30 and thereby move it to disengaged position. Therefore, it will be noted that the switching operation occurring at sometime between the period Δt will occur with zero current through the bridging contact 30.

Since the contact separation can occur during the current zero period, even though a current I_2 is flowing through the voltage path, complete separation of the co-operating contacts 30 can be achieved before there is opportunity for reverse current flow.

After there is complete separation of the co-operating contacts 30, the airgap will be sufficient to prevent the negative voltage V_{sp} from causing reverse current flow. Hence, the current rectifier 70 will not have to have a high negative breakdown voltage. However, since the voltage path comprising the inductor 90 and the rectifiers 80 remain in series with the source and load, the rectifiers 80 will have to have high negative breakdown voltage.

It should be noted that with the operation as described, the voltage rectifiers 80 do not have to sustain high load currents and are merely called upon to resist negative breakdown voltages whereas the current rectifier 70, although required to carry full load current, is not called upon to resist negative breakdown voltage.

Thus, at time t_3 when the load current I is at current zero, the current and the voltage branch I_2 will also have to be zero and hence, there will be complete interruption of the load current. This is true since from the time t_2 to time t_3 , namely the period Δt , current I_2 is equal to current I . Thus, in the above described operation, substantially currentless interruption is achieved without the necessity of a commutating reactor. At time t_1^* , the above described cycle will be repeated when the contacts 30 are again closed. It will be noted that the length of the period Δt represents current zero through the current path and hence, it would be desirable to increase this period of time to enable complete circuit interruption during current zero interval.

However, as the time Δt is increased, the magnitude of the current I_2 will also be increased and since this would represent larger current flow through a relatively high reactance voltage circuit, the losses of the rectifier would be increased. It is, therefore, desirable to use a substantially massless armature in the switching device 20 which could be the type of switching means discussed in Patent No. 2,732,451, assigned to the same assignee as the instant application which can effect circuit interruption in less than 10^{-4} seconds.

Thus, it is possible to have circuit interruption accomplished at a very short interval following the time t_2 and hence, the period Δt can be substantially reduced, as heretofore noted.

The maximum value of the current I_2 will be dependent upon the period of time Δt and since a large current I_2 would represent losses in the voltage path, a fast acting switch unit which reduces the period Δt will greatly increase the efficiency of the rectifier.

Thus, it will be noted that the novel circuitry of my invention incorporates a current path and a voltage path wherein substantially current zero conditions exist in the current path during the switching operation to thereby obtain currentless interruption. In this arrangement, the

current rectifier does not have to withstand a high back voltage since it is in series with the interrupting contacts.

The voltage rectifier, although required to have a high negative breakdown voltage, is not required to carry any substantial amount of the load current. Thus, with this arrangement, currentless interruption is achieved without a saturable reactor and maximum utilization of the desirable characteristics of the circuit components is achieved.

10 The circuit diagram of Figure 3 and its associated current voltage curves of Figure 4 illustrate an improvement of the circuitry of Figure 1.

At large magnitudes of voltages and currents, the IR losses in the voltage branch of the rectifier will be relatively large and thus, substantially reduce the efficiency of the rectifying device. In order to correct and avoid this situation, it is desirable to have a circuit arrangement wherein the voltage circuit is rendered inoperative during a major portion of the operating cycle and is triggered off only at a predetermined time which is immediately prior to the current-zero time of the current in the current path.

An arrangement wherein the voltage circuit can be triggered at a predetermined time is illustrated in the improved circuitry of Figure 3. In this arrangement, the switching apparatus 30 is schematically illustrated only as a simple switch and the magnet construction, closing and holding coils are eliminated for the sake of simplicity.

25 30 The voltage rectifier 80 of Figure 1 is replaced by the gas filled diode 27 in Figure 3. An additional component 20 is provided for the control of diode 27. The component 20 has an iron core 21 having an air gap 22 and a primary winding 23, a secondary winding 24 and a biasing or pre-excitation winding 34.

35 The pre-excitation winding 34 insures that the saturable core 21 will be saturated at the commencement of current flow, namely t_1 . At the time t_1 , no voltage will be induced into the secondary 24 of the saturable transformer 20 since there is no change of flux. Hence, during this period of time, there will not be sufficient plate voltage for the diode 27 and there will be no flow of current through the voltage circuit.

40 45 Accordingly, from time t_1 to time t_2 , the load current I will be equal to the current I_1 in the current path. At the time t_2 when the current I flowing through the primary 23 of the saturable transformer 20 is decreasing, the core 21 will become unsaturated. At this time, a voltage will be induced in the secondary winding 24 thereof.

50 55 The voltage induced in winding 24 at time t_2 is of proper polarity to permit current flow through the rectifier 25 to thereby charge the condenser 26. Hence, the voltage of the condenser 26 will now represent plate voltage of the gas diode 27.

60 The circuitry and components are properly designed so that the condenser 26 will supply a sufficient plate voltage to the gas filled diode 27 to cause the diode to breakdown and permit current flow through the voltage path.

65 Thus, at time t_2 which is immediately prior to the current zero time of the current I_1 through the current path, the voltage circuit will be triggered to render it effective. As current I_2 commences to flow in the voltage branch at time t_2 , the total load current I will be equal to current I_1 and I_2 .

70 75 It will again be noted that the current I_2 of the voltage branch will lag the current I_1 of the current branch. Thus, the current I_1 will pass through zero at time t_2 which is a period Δt prior to the time t_3 when the current I_2 of the voltage branch or the total current voltage I passes through current zero. Thus, at time t_2 , the current I_2 will be equal to the current I and the current I_1 in the current branch will be zero. Hence, the current

through the cooperating contacts 30 during the time of their separation is substantially zero.

Furthermore, it will be noted that the rate of increase of the current I_2 from the time t_0 to the time t_2 will be much less than the rate of increase as noted in the circuitry of Figure 1. This result will be due to the effect of the reactor 20 and hence, since the current I_2 flows for a shorter length of time, and has a smaller maximum value than that reached in the arrangement of Figure 1, the losses in the voltage path will be considerably reduced. Thus, with the novel circuitry of Figure 3, the losses in the voltage path become negligibly small.

It will be noted that the gas filled diode 27 can be replaced with a gas triode whereby the voltage circuit can be triggered off by connecting the secondary winding 24 across the grid cathode circuit of the triode. It will be noted of course that the diode 27 or a triode which may be used to replace it will not have to conduct the load current and hence, need not have the large magnitude current carrying characteristics of the rectifier 80.

However, this unit will have to be capable of sustaining the full back voltage and thus, have the characteristic of a high negative breakdown voltage.

The circuitry of Figure 3 also illustrates another improvement over that shown in Figure 1. In this arrangement, the rectifier 31, which compares to the rectifier 70 of Figure 1 is provided with a saturable core 32-33 in parallel therewith.

The current curve characteristics of this portion of the circuit is illustrated in Figure 5. The arrangement for by-passing the current diode 31 is provided for the sole purpose of reducing the maximum load current capacity requirement of this rectifier.

The sequence of operation of this parallel saturable core in coordination with the rectifier 31 is as follows: when the load current I commences to flow in the circuit at time t_1 , the reactor 32 will be unsaturated and hence, will represent a large impedance to the circuit as is well known in the art.

Thus, during this period of time, there will be an effective large impedance in parallel with the rectifier 31 and thus, all of the load current I_1 will flow through the rectifier 31. That is, when the switch 30 is first closed, all of the load current will flow through the rectifier 31 before the reactor 32 is saturated.

The current flowing through the rectifier 31 is identified as I_{31} in the current curve of Figure 5. However, after a short interval of time, namely at time t_6 , the reactor 32 will become saturated.

Thus, at time t_6 when the current I_1 has reached a sufficient magnitude to saturate the reactor 32, the winding 33 will be an effective short circuit across the rectifier 31.

Thus, as best seen in Figure 5, the division of current between the two units will be such that a major portion of the current I_1 will flow through the winding 33 (as shown by I_{33}) and very little current will flow through the rectifier 31 (shown by I_{31}).

Accordingly, during the major portion of the cycle of operation of the magnetic rectifier, the rectifier 31 will be substantially short circuited by the winding 33 due to the saturated condition of the reactor 32.

Near the end of the conducting cycle, namely at time t_7 , the reactor 32 will become unsaturated and hence, present a high impedance to this circuit as is well known in the art.

At this point, the current division between the components 31 and 33 will again change since the reactor 32 will represent a large impedance in parallel with the relatively small impedance of the rectifier 31. Thus, between time t_7 and t_2 , as seen in Figure 5, a major portion of the current I_1 will flow through the rectifier 31 (identified as I_{31}), and little or no current will flow through the reactance winding 33.

It will be noted by utilizing this parallel reactor 32, as a switching device to alternately divert the current to

and from the rectifier 31, depending on the magnitude of the current I_1 , the efficiency of the circuitry can be greatly increased. That is, since the rectifier 31 is no longer required to conduct the major portion of the load current, the IR drop thereacross will be relatively small. Since the reactance of the winding 33 during a major portion of the conducting cycle is relatively small, the IR drop thereacross will also be very small even though the magnitude of I_1 should reach great proportions.

Additional means may be provided in order to limit the back current flow in the circuitry from the time t_2 to the time t_1 .

It will be noted that heretofore, a large commutating or saturable reactor is used in series with the circuits providing a relatively long step circuit to insure complete separation of the contacts during the step and at a step immediately following the separation in order to eliminate back flow of current.

As heretofore noted, the contacts of my novel circuitry opens under substantially current zero conditions and hence, the possibility of reverse current flow is relatively small due to the safety period Δt . However, as an added precaution to insure that there will be no backflow of current, a small saturable reactor 29 may be inserted in the current path.

The saturable reactor 29 can be pre-magnetized (not shown) in a manner well known in the art so that a step current will occur during the switching operation.

It will be noted that in the improved circuit design of Figure 3 wherein a gas tube 27 is substituted for the rectifiers 80, the overall efficiency of the switching circuit can be improved due to the reduced IR losses. Thus, for example, assuming that with the use of dry rectifiers 70, an efficiency of 85% is achieved (Figure 1) $\frac{1}{2}$ of the losses can be eliminated by using a gas filled tube as shown in Figure 3. Thus, if two rectifiers 80 are replaced by a single gas filled tube, the efficiency can be increased to 92 and $\frac{1}{2}$ percent. If the number of dry rectifiers 80 required in the circuitry of Figure 1 is five, the efficiency of the circuit shown in Figure 3 by replacing the five dry rectifiers with a single gas filled tube 27 can be increased to 97%. Accordingly, the arrangement of Figure 3 is much more economical and obtains a much higher efficiency than the circuit arrangement of Figure 1.

A modified arrangement whereby the back current flowing through cooperating contacts 30 can be reduced is illustrated in Figure 6. This arrangement illustrates only a portion of the circuitry shown in Figure 1 but is provided with the additional transformer unit 16 which couples the current and voltage paths.

The transformer 16 has a primary winding 90 which is in series with the voltage path and serves the dual function of energizing the transformer 16 and performs the same function as the inductor 90 as seen in Figure 1.

The transformer has a secondary winding 17 which is connected in series with the variable resistor 17 and in parallel with the condenser 19 and the cooperating contacts 30.

The operation of this unit is as follows: commencing at time t_2 until time t_3 , as seen in Figure 4, the current I_2 in the voltage path will be decreasing at a constant rate. Accordingly, a substantially constant direct current potential will be introduced into the secondary winding 17 due to the constant rate of decrease of the current I_2 .

By proper adjustment of the variable impedance 17, the commutating current I_k resulting from the induced E. M. F. in the secondary winding 17 can be made substantially equal to the back or return current I_r of the rectifier 70. That is, the system is so arranged that the current I_k will compensate for the back or return current I_r across the cooperating contacts 30.

Further improvements over the arrangement shown in Figure 3 to increase the efficiency thereof are shown in Figures 7 and 9 and explained by the use of the current curves of Figures 8 and 10.

The inductance 28, connected in series with the voltage path, will have a back E. M. F. which will be detrimental to the circuit. That is, during the period Δt from time t_2 to t_3 , when the current I_2 in the voltage branch is decreasing, an inductor 28 will tend to maintain the current at its present value and hence, a large back E. M. F. will result therein. The arrangement shown in Figures 7 and 9 provides a circuit whereby the inductor can be short circuited at this predetermined period of time in order to eliminate its undesirable effect on this circuit. Thus, for example, as seen in Figure 7, a diode 40 can be placed in parallel with the inductance 28.

During the period of time from t_2 to t_3 when the current I_2 is increasing, the voltage V will be negative across the diode 40 and hence, there will be no conduction therethrough.

However, at the time t_2 when the current I_1 is at current zero, the current I_2 will commence to decrease.

The induced E. M. F. will be of proper polarity to break down the tube 40. That is, the voltage V will now be positive as indicated by V' and hence, there will be conduction through the diode 40. Accordingly, the diode 40 will now represent a substantial short circuit across the inductor 28 and thereby render this unit practically ineffective.

A modified arrangement of that shown in Figure 7 is illustrated in Figure 9 wherein the inductor 28 serves as a primary winding for the transformer 42. The secondary winding 44 and the transformer 42 is connected in series with the rectifier 45.

Thus, for example, from the time t_2 to the time t_3 when the current I_2 is increasing as shown in Figures 4 and 10, the rectifier 45 will block any flow of current from the secondary 44. Hence, the equivalent circuit during this period of time from t_2 to t_3 will be a high impedance across the inductor 28. However, at time t_3 when the current I_2 in the voltage branch commences to decrease following the time t_3 , the voltage induced in the secondary winding 44 of the transformer 42 will be of proper polarity to permit conduction through the rectifier 45. This of course will represent a short circuit on secondary winding 44, the equivalent circuit thereof being a short circuit across the primary winding 28.

Accordingly, the novel arrangement shown in Figures 7 and 9 will induce a substantial short circuit across the inductor 28 during the period Δt to eliminate any undesired effect at the back of the E. M. F. of this unit.

Figure 11 shows an arrangement whereby my novel parallel voltage current path arrangement can be utilized in connection with an alternating current switch.

In the circuitry of Figures 1 and 3, the arrangement is designed primarily for use with a rectifying unit whereas in the arrangement shown in Figure 11, the principle and concepts of my invention are applied to a circuit interrupting device. In this arrangement, there is current flow from the source 50 to the load 63 through point A of the stationary contact 52, the movable contact 54 to point B. Thus, during normal operation, the rectifier 58 in the current path and the rectifiers 59 and in the voltage path are not introduced in the circuit. The movable contact 54 is pivoted at point 62 and may be controlled by the solenoid 55.

For the sake of simplicity, the energization of the opening coil 55 is illustrated as being achieved by the series circuit members, the battery 56 and the closing circuit 57.

It will be noted that the opening coil 55 may be energized in any desirable manner. Thus, for example, it can also be energized from the load current and be responsive to predetermined overload conditions.

When the solenoid 55 is energized, it attracts the arm of the movable contact downwards so that it rotates in counterclockwise direction around the pivot 62. This will immediately divert current flow from the arm 54 to the path consisting of the arcing horns 52, 53 and the cur-

rent rectifier 58. That is, current I_1 will now flow through the arcing horns and the rectifier in the current path. Since additional impedance has been introduced into the current path, some of the load current I will be diverted to the voltage path and thus, a current I_2 will flow through the voltage rectifier 59.

Since the magnetic field of the arc will tend to blow the arc existing between the arcing horns 52 and 53 upward, there will be complete interruption of the current in the current path when the current I_1 passes through current zero since rectifier 58 will prevent reverse current flow.

The current I_2 , which lags current I_1 , as heretofore noted in connection with the Figures 1 and 2, will pass through current zero at a period Δt following the interruption in the current path and reverse current will be prevented from flowing due to the rectifiers 59.

Thus, during this following half cycle, the switch 60b may be opened under currentless conditions to achieve complete interruption of the circuit. It will be noted that the pivot arm 54 and the connecting link 61 of the switch 60b may be inter-connected with the lost action as is wellknown in the art so that the cooperating contacts 60b open in a period in excess of Δt following the disengagement of the cooperating contacts 52, 54 by solenoid 55. Accordingly, after the two switches 51 and 60b have been opened the current circuit is completely interrupted.

Thus, in essence, my invention relates to a novel method of circuit interruption wherein a current path containing the main cooperating contacts for circuit interruption and a current rectifier is shunted or bridged by a voltage path containing a voltage rectifier and an inductance.

By proper component design or adjustment, the current in the voltage path can be maintained at substantially zero value during a major portion of the operating cycle and commence to flow and lag the current in the current path immediately prior to current zero conditions thereof.

Thus, by making the switching apparatus in the current path an electromagnetic switch device, the cooperating contacts can be disengaged under substantially currentless conditions even though there continues to be a slight current flow in the voltage path.

After the current flow in the current path has reached current zero conditions, the voltage rectifier will prevent reverse current flow therein and since the electromagnetic switch is completely opened, there will be no reverse current flow in the current path. Hence, complete interruption of the circuit is achieved with sparkless operation of the cooperating contacts without the use of a commutating reactor.

In the foregoing, I have described my invention only in connection with preferred embodiments thereof. Many variations and modifications of the principles of my invention within the scope of the description herein are obvious. Accordingly, I prefer to be bound not by the specific disclosure herein but only by the appending claims.

I claim:

1. In a switching device having a first path and a current path in parallel, said parallel combination of said first and current paths being in series with a source and load, said current path comprising an electromagnetic switching device and a current rectifier, said first path containing an inductor and a first rectifier.

2. In a switching device having a first path and a current path in parallel, said parallel combination of said first and current paths being in series with a source and load, said current path comprising an electromagnetic switching device and a current rectifier, said first path containing an inductor and a first rectifier, said voltage rectifier capable of withstanding full negative voltage of said source.

3. In a switching device having a first path and a current path in parallel, said parallel combination of said first and current paths being in series with a source and load, said current path comprising an electromagnetic switching device and a current rectifier, said first path containing an inductor and a first rectifier, and means to render said first circuit effective immediately prior to current conditions in said current path.

4. In a switching device having a first path and a current path in parallel, said parallel combination of said first and current paths being in series with a source and load, said current path comprising an electromagnetic switching device and a current rectifier, said first path containing an inductor and a first rectifier, the total current flowing from said source to said load divided between said current path and said first path at a predetermined time within the operating cycle in such a manner that the current through the first path lags the current through the current path.

5. In a switching device having a first path and a current path in parallel, said parallel combination of said first and current paths being in series with a source and load, said current path comprising an electromagnetic switching device and a current rectifier, said first path containing an inductor and a first rectifier, and means to render said first circuit effective immediately prior to current conditions in said current path, said electromagnetic switch interrupting the circuit at substantially currentless conditions.

6. In a switching device having a first path and a current path in parallel, said parallel combination of said first and current paths being in series with a source and load, said current path comprising an electromagnetic switching device and a current rectifier, said first path containing an inductor and a first rectifier, and means to render said first circuit effective immediately prior to current conditions in said current path, said electromagnetic switch opening when the current flow in said current path is at current zero.

7. In a switching device having a first path and a current path in parallel, said parallel combination of said first and current paths being in series with a source and load, said current path comprising an electromagnetic switching device and a current rectifier, said first path containing an inductor and a first rectifier, said first path rendered ineffective during the major portion of the operating cycle.

8. In a switching device having a first path and a current path in parallel, said parallel combination of said first and current paths being in series with a source and load, said current path comprising an electromagnetic switching device and a current rectifier, said first path containing an inductor and a first rectifier, said first path being an infinite impedance during the major portion of the current conduction through said last mentioned path.

9. In a switching device having a first path and a current path in parallel, said parallel combination of said first and current paths being in series with a source and load, said current path comprising an electromagnetic switching device and a current rectifier, said first path containing an inductor and a first rectifier, said first path rendered ineffective during the major portion of the operating cycle.

10. In a switching device having a first path and a current path in parallel, said parallel combination of said first and current paths being in series with a source and load, said current path comprising an electromagnetic switching device and a current rectifier, said first path containing an inductor and a first rectifier, the load current from said source to said load divided between said current path and said first path at a predetermined time prior to current zero in said current path.

11. In a switching device having a first path and a current path in parallel, said parallel combination of said first and current paths being in series with a source and

load, said current path comprising an electromagnetic switching device and a current rectifier, said first path containing an inductor and a first rectifier, said first rectifier being a gas diode, means to control the plate voltage of said diode, said means rendering said diode non-conductive during the major portion of said cycle in said circuit.

12. In a switching device having a first path and a current path in parallel, said parallel combination of said first and current paths being in series with a source and load, said current path comprising an electromagnetic switching device and a current rectifier, said first path containing an inductor and a first rectifier, said first rectifier being a gas filled tube, means to control the conductivity of said gas filled tube, said means rendering said gas filled tube operative immediately prior to current zero condition in said current path.

13. In a switching device having a first path and a current path in parallel, said parallel combination of said first and current paths being in series with a source and load, said current path comprising an electromagnetic switching device and a current rectifier, said first path containing an inductor and a first rectifier, means to render said first rectifier effective, said means comprising a saturable transformer having a primary and secondary winding, said primary winding of said saturable transformer connected in series with said source and said load, said secondary winding connected in series with a rectifier, said rectifier poled to prevent current flow through said secondary winding when said primary winding is energized by an increasing current.

14. In a switching device having a first path and a current path in parallel, said parallel combination of said first and current paths being in series with a source and load, said current path comprising an electromagnetic switching device and a current rectifier, said first path containing an inductor and a first rectifier, the total current flowing from said source to said load divided between said current path and said first path at a predetermined time within the operating cycle in such a manner that the current through the first path lags the current through the current path, a saturable reactor having a primary winding, said primary winding of said saturable reactor shunting said current rectifier, said primary winding effective as a substantially short circuit across said current rectifier during the major portion of a conducting cycle of said circuit.

15. In a switching device having a first path and a current path in parallel, said parallel combination of said first and current paths being in series with a source and load, said current path comprising an electromagnetic switching device and a current rectifier, said first path containing an inductor and a first rectifier, the total current flowing from said source to said load divided between said current path and said first path at a predetermined time within the operating cycle in such a manner that the current through the first path lags the current through the current path, means to short circuit said inductor when the current through said first path is decreasing.

16. In a switching device having a first path and a current path in parallel, said parallel combination of said first and current paths being in series with a source and load, said current path comprising an electromagnetic switching device and a current rectifier, said first path containing an inductor and a first rectifier, the total current flowing from said source to said load divided between said current path and said first path at a predetermined time within the operating cycle in such a manner that the current through the first path lags the current through the current path, means to short circuit said inductor when the current through said first path is decreasing, said means comprising a diode connected in parallel with said inductor, said diode operated for current induction only during current decrease in said inductor.

17. In a switching device having a first path and a current path in parallel, said parallel combination of said first and current paths being in series with a source and load, said current path comprising an electromagnetic switching device and a current rectifier, said first path containing an inductor and a first rectifier, the total current flowing from said source to said load divided between said current path and said first path at a predetermined time within the operating cycle in such a manner that the current through the first path lags the current through the current path, means to short circuit said inductor when the current through said first path is decreasing, said means comprising a transformer having said inductor as a primary winding thereof, a secondary winding for said transformer, said secondary winding connected in series with a rectifier, said last mentioned rectifier operated to prevent current flow through said secondary winding when the current flow through said primary winding is increasing.

18. In a switching device having a first path and a current path in parallel, said parallel combination of said first and current path being in series with a source and a load, said current path comprising an arc extinguishing means and a current rectifier, said first path containing a first rectifier, said arc extinguishing means and said current rectifier normally bridged by a movable contact, opening means to remove said movable contact parallel path from said arc extinguishing means

and said current rectifier to thereby divert current from said source through said current path and said first path.

19. In a switching device having a first path and a current path in parallel, said parallel combination of said first and current path being in series with a source and a load, said current path comprising an arc extinguishing means and a current rectifier, said first path containing a first rectifier, said arc extinguishing means and said current rectifier normally bridged by a movable contact, opening means to remove said movable contact parallel path from said arc extinguishing means and said current rectifier to thereby divert current from said source through said current path and said first path, switching means to interrupt said first path following the removal of said shunt path from said arc extinguishing means and said current rectifier.
